UNITED STATES PATENT OFFICE.

GUSTAVE E. FRANQUIST, OF NEW YORK, N. Y.

DEFORMATION-CLUTCH.

No. 839,468.

Specification of Letters Patent.

Patented Dec. 25, 1906.

Application filed December 28, 1905. Serial No. 293,059.

To all whom it may concern:

Be it known that I, GUSTAVE E. FRANQUIST, a citizen of the United States, residing at the city of New York, in the borough of 5 Manhattan and State of New York, have invented certain new and useful Improvements in Deformation-Clutches, of which the following is a full, clear, and exact description.

My invention relates to clutches, and pertains particularly to the provision of a clutch which shall have all the characteristics of a friction-clutch with respect to soft and gradual starting and stopping action, 15 but which shall be virtually positive or interlocking during the period of its driving engagement.

A further object of the invention is to provide a clutch of extremely small diameter and 20 rotative inertia, but which shall be capable of transmitting the heaviest driving forces which occur in practice.

Other objects of the invention are to construct a practical form of clutch which shall be simple in construction, extremely durable, 25 and having a minimum number of parts liable to disarrangement or failure of any sort.

With these and other objects in view my invention consists in the construction, combination, location, and arrangement of parts, 30 all as will be more fully hereinafter described, as shown in the accompanying drawings, and finally particularly pointed out in the appended claims.

In the drawings, Figure 1 is a sectional view showing a clutch embodying the principles of my invention. Fig. 2 is a similar view, partly in elevation, showing the parts in their driving relation. Fig. 3 is a sectional view on the line III III of Fig. 1. Fig. 4 is a similar sectional view on the line IV IV of Fig. 2. Fig. 5 is a sectional view showing a slightly-modified form of construction. Fig. 6 is a similar view showing another slight modification. Fig. 7 is a sectional view illustrating a still further modified form of clutch embodying the principles of my invention, and Fig. 8 is a transverse section of the same.

The essential principle which I have discovered and make use of in the practical constructions hereinafter described depends upon the elastic deformation of a resilient member under the torque stresses of the driving transmission. Stated in other words, 55 the essential characteristic of clutches em-

bodying the principles of my invention is a comparatively thin web or shell of resilient substance through which the power is transmitted and which takes on a deformed outline, producing an interlocking engagement of the clutch-surfaces, the degree of which is proportional to the power transmitted. 60

In carrying out the invention I prefer to employ clutches having coaxial surfaces of 65 revolution which can be made to engage one another frictionally and which subsequently become deformed or distorted, so as to partially interlock with one another and secure a practically positive clutching engagement. 70

Referring now to the drawings, in which I have illustrated practical forms of construction embodying the foregoing principle and in which like parts are designated by the same reference-sign whenever they occur, 1 75 denotes a driving-shaft, upon which is fixed the fly-wheel 2, having a clutch-casing 3, formed with an internal annular face 4.

Referring to Figs. 1, 2, and 3 of the drawings, it will be seen that the face 4 is conical 80 or flaring in outline and has at a plurality of points therein spaced pockets 5 for a purpose which will later appear. 6 indicates the driven shaft, which is conveniently provided with an enlarged extension or head 7 within 85 the clutch and through which the driving forces are transmitted. For this purpose the head or extension 7 is splined to the driven clutch member 8, which has a tubular casing 9 extending along the driven shaft. 90 10 denotes a collar within this casing upon which a tension-spring 11, supported against the head or extension 7, constantly bears to throw the clutch member 8 into clutching relation. 12 denotes the usual or any ordinary 95 form of thrust-bearing collar for positively moving the tubular casing 9 longitudinally when desired, so as to disengage the clutch members.

The features thus far described are not 100 essentially different from the ordinary and well-known form of cone friction-clutch, and it is in the construction, location, and arrangement of the parts hereinafter described that the invention particularly lies. 105

Referring particularly to Figs. 3 and 4 of the drawings, I have illustrated an arrangement, for securing an initial frictional engagement and a subsequent positive or interlocking engagement of the clutch-surfaces. 110 The driven clutch member 8 is formed upon its exterior peripheral surface with a plural-

ity of pockets 13, generally similar in form and number to the pockets 5 above mentioned. These may be variously shaped; but I have found by practical experiment that satisfactory results are secured by making them in the form of shallow V-shaped grooves extending along the elements of the cone-surfaces. 14 and 15 denote conical webs or shells, which I shall term the "resilient" or "deformation" members, and which respectively have projections 16 17, corresponding in form and number to the recesses 5 and 13, and which are adapted to be received therein. By making the pockets 5 and 13 and the projections 16 and 17 V-shaped their engaging faces have a camming or wedge action when they are pressed tangentially together. The deformation members each have annular faces or surfaces, which are normally coaxial perfect surfaces of revolution. Each of the deformation members is supported wholly by its lugs or projections 16 17 from the driving and driven clutch members 3 and 8, respectively.

25 The operation is as follows: Imagine the parts in unclutched reilation, as shown in Fig. 1, in which the tubular casing 9 and the driven member 8 are positively pressed to their right-handed relation by the collar 12.

30 Under these circumstances the resiliency of the deformation members 14 and 15 will cause them to assume their perfect circular outline, whereupon their engaging surfaces will be true coaxial surfaces of revolution.

35 The rotation of the driving member 3 will not be effective to transmit movement to the driven clutch member, the deformation-surfaces sliding idly over one another at this time. If now pressure is released from the

40 collar 12, the spring 11 becomes effective to force the driven clutch member 8 to the left in Figs. 1 and 2, so that the opposed conical surfaces of the deformation members come more closely into contact and frictionally engage one another, so as to transmit a part of the driving force. In starting the surfaces slide over one another, as is usual with coned or any desirable form of clutch until the driven mechanism has attained a certain

45 speed. It is now merely necessary to still further release pressure from the spring 11, whereupon it presses the oppositely-coned surfaces into tight engaging relation, and the full torque of the driving member is

50 transmitted therethrough. On account of the normal forces of the clutching engagement, and more particularly the tangential forces of the driving engagement, the deformation members presently become warped

55 or deformed, as shown in Fig. 4. It is evident that the amount of deformation or warping is generally proportional to the power transmitted, and therefore to its need, the deformation being greater for large driving stresses than in cases where the forces

are small. The clutch therefore automatically accords itself to the wants of its conditions and transmits a great or small force with perfect efficiency.

I will now describe a slightly-modified form of construction which is shown in Fig. 5 and in which the driving and driven members are indicated at 18 and 19, respectively. The deformation member in this instance comprises a spiral band 20, anchored at its two ends 21 and 22 to the interior wall of the driving member 18. The surface of the driven member 19 varies from a true surface of revolution in any way—as, for example, by making it polygonal with a plurality of sides 19^a 19^b. With this form of construction the interior surface of the deformation member 20 preserves a surface of revolution generally coaxial with the uppermost points of the driven member until the driving forces become so great as to deform the band into a polygonal shape corresponding to that of the driven member. It is evident that when this form of clutch is once engaged it acquires the characteristics of a spiral-band clutch, as well as those of a deformation clutch.

A further slightly-modified form of construction which equally embodies the essential features of my invention is particularly shown in Fig. 6. This construction is of particular practical utility in the case of lathe-carriages, being designed to take the place of the usual apron-clutch which operates the carriage-feed. 23 indicates the driving member, and 24 the driven shaft, having a clutch member 24' slidably thereon. The two clutch members are in alinement with one another and have parallel opposed faces 25 and 26. Each of the faces 25 and 26 has spaced pockets 27 and 28 therein. The deformation members are in this case shown in the form of flat disks or rings 29 and 30, having lateral teeth 29' and 30', which are contained in the pockets 27 and 28, previously described. 31 indicates a stem which projects from the member 24' axially through the driving member 23 and through the driven shaft 24 and has at its end a threaded portion 32, engaging the hand-wheel 33. By this means rotation of the hand-wheel 33 is effective to draw the faces 25 and 26 toward one another and cause the deformation members to frictionally engage, as in the preceding form of my invention. By virtue of the frictional engagement and the torque transmitted the deformation members become distorted and interlock in the same way as in the previous case.

A practical form of my invention in which a single deformation-surface of cylindrical form is employed is illustrated in Figs. 7 and 8, in which 34 indicates the driving-shaft, and 35 the frame or casing of the clutch member rotating therewith. The part 35 is made with an internal annular recess or cavity 36,

within which is located a contractible ring 37, which is anchored to the casing at 38 and extends annularly around the same, terminating in a free end 39, which under certain circumstances can be moved tangentially to contract the ring. For this purpose it is provided with an eye 40, into which projects a short arm 41 of a lever fulcrumed at 42 and having an arm 43, by which it is moved to contract the ring. 44 indicates a cam-roller upon the end of the arm 43, which may contact with a conical cam 45, a longitudinal movement of which is effective to move the arm as above described. These particular details are relatively unimportant, it being merely essential to provide a contractible ring 37, having an internal annular face 48. Instead of making the face 48 a true surface of revolution I form portions of it, 49, slightly recessed or cut away from a proper cylindrical outline. In other words, the face 48 presents a series of surfaces 48', which are truly concentric with the axis of the clutch, alternated by slightly-recessed or cut-away portions which would not contact with the true cylindrical outline. Within the member 37 is disposed the deformation member proper; 50, which in this case comprises a thin cylindrical shell or ring with integral projecting lugs 50'. 51 indicates the driven member of the clutch, which has recesses or pockets 52, which contain the lugs 50', above mentioned, and retain the deformation member in proper relation. The operation of this form of my invention is as follows: When the clutch is idle, the cam 45 is in the position shown in Fig. 4, and the ring 37 is by means of its natural resiliency held in its expanded relation and out of contact with the deformation member 50. Under these circumstances the driving member rotates relatively to the driven member 51, the ring 37 passing idly over the deformation-surface. When now it is desired to apply the clutch, the cam 45 is moved so as to rock the lever 43, whereupon the ring 37 is contracted so as to frictionally engage the deformation-surface beneath. This deformation occurs at the points 48' around its periphery, and by virtue of the driving torque, together with the clutching pressure, the deformation ring or shell 50 becomes distorted, so as to project into the recesses 49 in the contracting-ring. When this occurs, the clutch becomes virtually an interlocking or positive clutch, and any further slipping between the driving and the driven member is impossible.

It will be seen that I provide a clutch in which the starting engagement is purely frictional, so as to secure the soft and gradual action which is desirable, but that after the clutch is once fully in engagement it becomes virtually a positive or interlocking clutch on account of the deformation-surfaces, which are the essential characteristic of the invention.

What I claim is—

1. A clutch comprising a driving and a driven member having coaxial surfaces, and means actuated by the torque of the driving transmission for distorting or deforming such surfaces out of a true circular outline, the amount of such deformation being proportional to the torque of the driving transmission. 70

2. In a friction-clutch, a driving member, 75 a driven member on the same axis therewith, said driving member and said driven member each having a friction-surface normally a surface of revolution and concentric with said axis, and means whereby said surfaces 80 are deformed by the torque of the driving transmission out of said concentric relation with said axis.

3. A clutch comprising a driving and a driven member having coaxial surfaces arranged to frictionally engage one another, and means whereby such surfaces become deformed into interlocking or positive engagement under the influence of the driving transmission. 85 90

4. A clutch comprising a driving and a driven member having coaxial webs or shells, and means whereby said webs or shells are distorted into interlocking or positive engagement by the driving transmission. 95

5. A clutch comprising a driving and a driven member having coaxial surfaces with pockets therein, and a pair of deformation members having lugs contained in said pockets and adapted to frictionally engage one 100 another.

6. In a friction-clutch, a driving and a driven member arranged to be axially moved toward one another, said members having frictionally-engaging surfaces, said surfaces 105 being initially capable of unlimited relative rotation when the clutch is thrown to its position of complete engagement, and means for deforming said surfaces into positive or interlocking engagement when the torque of the driving transmission exceeds a predetermined value by reason of the expulsion of the oil from between the surfaces. 110

7. In a friction-clutch, a driving and a driven member arranged to be axially moved 115 toward one another to the position of complete clutching engagement in any rotative relation, said members having frictionally-engaging surfaces, said surfaces being initially capable of unlimited relative rotation 120 when the clutch is thrown into said fully-engaged relation, and means for deforming said surfaces into positive or interlocking engagement when the torque of the driving transmission exceeds a predetermined value by 125 reason of the expulsion of the oil from between the surfaces.

8. A clutch comprising a driving and a driven member, a deformation web or shell having integral lugs projecting therefrom, 130

- and means for supporting said web or shell wholly from said lugs whereby it is distorted under the influence of the driving engagement.
5. 9. A clutch comprising a driving and a driven member, a deformation web or shell having integral lugs projecting therefrom, and means whereby the driving torque is transmitted through said lugs, whereby said
10. web or shell is deformed into interlocking engagement with the other clutch member.
10. 10. A clutch comprising a driving member having a series of pockets, a deformation web or shell having lugs contained in said pockets, and a driven member having a friction-surface adapted to be engaged by said web or shell so as to deform the same into interlocking engagement with the other clutch member.
15. 11. A clutch comprising a driving member having a series of pockets, a deformation web or shell having lugs contained in said pockets, a driven member also having pockets and a second deformation web or shell having integral lugs contained in such pockets, said webs or shells being adapted to frictionally engage one another.
20. 12. A clutch comprising driving and driven members having pockets and a pair of deformation members having integral lugs with cam-surfaces contained in said pockets, and having surfaces adapted to frictionally engage one another.
25. 13. In a clutch, a driving member having an internal conical surface with a series of pockets therein, a conical deformation web or shell having integral lugs contained in said pockets, and a driven member adapted to frictionally engage said web or shell so as to deform the same and produce locking engagement therewith.
30. 14. A clutch comprising a driving member having an internal conical surface with a series of pockets, a conical web or shell with integral lugs contained in said pockets, a driven member also having a series of pockets, and a conical web or shell having lugs projecting into said pockets, and means for moving said driven member longitudinally so as to engage the surfaces of said webs or shells.
35. 15. A deformation-clutch comprising driving and driven members each of which is deformable and each having a plurality of lugs thereon; and means for exerting a tangential
- force on each of said lugs, whereby the members are deformed into interlocking or positive engagement. 55
16. A deformation-clutch comprising driving and driven members of resilient material, and both of which have a normally circular outline, and means for altering said outline when the friction between the members exceeds a certain value.
17. A deformation-clutch comprising driving and driven members supported at equal angularly-spaced points, and capable of becoming deformed from a true cylindrical outline, and means for imparting oppositely-directed tangential stresses to the members whereby they are deformed. 60
18. A friction-clutch comprising a resilient or deformation member having a true surface of revolution in its normal shape, means engaging said surface of revolution also having a true surface of revolution for transmitting the driving stresses, and means whereby both members are deformed out of a surface or revolution thereby. 70
19. In a friction-clutch, a driving and a driven member arranged to be axially moved toward one another to the limit of clutching movement in any position of rotative relation, said members having frictionally-engaging surfaces, said surfaces being initially capable of unlimited relative rotation when the clutch is fully engaged, and means for deforming said surfaces into positive or interlocking engagement when the torque of the driving transmission exceeds a predetermined value by reason of the expulsion of the oil from between the surfaces. 75
20. A friction-clutch comprising a resilient or deformation member, a power-transmitting member, and means for deforming both of said members into interlocking relation with one another. 80
21. A clutch comprising driving and driven members which are elastic or resilient so as to be capable of deformation out of a true circular outline by the driving transmission, and means for limiting such deformation to a degree within the elastic limit of the material. 85
